UNITED STATES PATENT OFFICE.

THOMAS M. NORTH, OF BROOKLYN, NEW YORK, ASSIGNOR TO ROBERT HOE,
THEODORE H. MEAD, AND CHARLES W. CARPENTER, OF NEW YORK, N. Y.

SHEET-DELIVERY APPARATUS FOR PRINTING-MACHINES.

SPECIFICATION forming part of Letters Patent No. 591,223, dated October 5, 1897.

Application filed February 6, 1895. Serial No. 537,532. (No model.)

To all whom it may concern:

Be it known that I, THOMAS M. NORTH, a subject of the Queen of Great Britain, residing at the city of Brooklyn, county of Kings, 5 and State of New York, have invented certain new and useful Improvements in Front Sheet-Deliveries for Cylinder Printing-Machines, fully described and represented in the following specification and the accompanying drawings, forming a part of the same.

This invention relates to that class of printing-machines in which printed sheets received from an impression-cylinder require to be delivered flat upon a piling-table.

15 The object of the invention is to provide a delivery apparatus for such a printing-machine by which the sheets are not only delivered printed side up, but without the freshly-printed surface having had contact with delivery-tapes or other mechanism whereby smutting might occur.

25 The invention consists in a sheet-delivery carriage having rotating devices operating by nipping contact to nip and hold the sheet during the outward movement of the carriage and to positively roll the sheet from the carriage onto the piling-table during its return stroke, as will hereinafter be more particularly described and finally claimed.

30 A practical embodiment of the invention is shown in the accompanying drawings, in which—

Figure 1 is a side elevation of so much of a printing-machine as is necessary to illustrate this invention. Fig. 2 is a plan view of the same. Fig. 3 is an elevation on section-line 3 4, showing the sheet-carriage at the end of the outward stroke. Fig. 4 is a similar view on section-line 3 4, showing the carriage returning and depositing the sheet on the pile. Fig. 5 is an enlarged side view of part of the carriage, showing it at the end of its return stroke toward the cylinder. Fig. 6 is a similar view showing the carriage with the paper after having traveled a short distance in its delivery stroke. Fig. 7 is a plan view of the parts shown in Fig. 5.

45 So much of a cylinder or flat-bed printing-machine as is necessary to illustrate these 50 improvements is shown in the drawings, and beyond pointing out that the impression-cylinder C and form-carrying reciprocating flat bed D are similar to like devices in this well-

known class of printing-machines no further description thereof is required for those 55 skilled in this art, since the function of this delivery apparatus is to receive the printed sheet from the impression-cylinder C while it travels in a direction indicated by the arrow in Fig. 1 and deliver the same on the piling-table, so that the precise structure of the printing devices is immaterial.

The delivery-carriage consists in part of two opposite heads A B, which slide on longitudinal guide-rods 21 31, supported by the 65 framework, said heads A B being connected together by rods 40 44 and shafts 41 42 43. The rod 44 supports projecting fixedly from it a number of horizontal fingers 46, which descriptively may be said to constitute a horizontal carrying-frame, said fingers, extending both sides of the said rod 44, having heels long enough to reach into recesses in the delivery-roller 50 on the shaft 43 and whose points project toward the impression-cylinder. 70 Above these fingers there are companion guides 51, that are hung upon the rod 40, which guides extend rearwardly over the heels of said fingers and forward toward the impression-cylinder for a considerable distance over the fingers. The delivery-roller 50 is mounted on the shaft 43, which is provided at one end with a pinion 60, that is geared with an intermediate 61, mounted on a stud, and which carries pivoted on one face 75 a pawl 9, that engages with a ratchet-wheel 62, fast to a wheel 63, the sleeve carrying which wheels 62 63 turns freely on the stud of the intermediate 61, the wheel 63 engaging with a rack 64, supported by the framework, 80 by which arrangement said wheel 63 is rotated in a direction corresponding with the travel of the delivery-carriage, and moving in one direction drives the roller 50 through the ratchet-wheel 62, ratchet 9, intermediate 61, 85 90 and pinion 60.

For coöperation with the delivery-roller 50 the rock-shaft 41 is provided with arms 80, at the forward ends of which are carried friction-rolls 90, that press the margins of the 100 sheets upon the delivery-roller 50, and thus cause the sheets to be moved thereby, which margin-rolls are raised out of their active positions through a rock-arm 81, that collides for that purpose with a stop 19, fixed to the 105 framework, their raised position being se-

cured by a locking-lever 82, pivoted to the delivery-carriage and gravitating into position to engage said rock-arm, as in Fig. 5, said locking-lever 82 being tripped to free the 5 rock-arm 81, and thus allow the margin-rolls to descend and rest upon the delivery-roller 50 by means of a tappet 6, fixed to the frame, engagement with which tilts said lever, as in Fig. 6, these operations being performed at 10 proper times, according to the positions which the delivery-carriage attains in its reciprocatory movements.

The shaft 42 supports forwardly-projecting sheet-stops 3, whose forward ends are bent 15 downward, so that they may intercept the pathway of the sheets and act to temporarily arrest their forward movement. This shaft 42 is supported in arms 22, fast upon the shaft 41, and hence is raised and lowered by its 20 rocking movements, and the shaft 42 is rocked to raise and lower the stops 3, as required, by means of an arm 8, fast to the shaft 42 and having its ends playing in an elongated hole in a detent-arm 2, rising from the carriage. 25 This carriage is reciprocated by means of racks 35 36, attached to pairs of running sleeves 20 30, which slide on the guide-rods 21 31, being driven by pinions 37 at opposite sides of the carriage, the shaft 5 on which 30 said pinions are mounted being rotated by bevel-wheels 38 39 through a vertical shaft 71, which in turn is driven by bevel-wheels 72 73 from a pinion 74, rotated in opposite directions by suitably-timed movements of a 35 swinging segment-rack 75, actuated by a rod 76 from a crank-wheel 77. For coöperation with this delivery-carriage there are provided near the impression-cylinder C conductors or guides 7, which are supported by a rod 18 and 40 extend from near the surface of the impression-cylinder outward to a point at or near that at which the fingers reach when they nearest approach the impression-cylinder, thus forming with the said fingers a continuous 45 guide for the sheets from the impression-cylinder to the stops 3.

For carrying the sheets outward from the impression-cylinder into position on the fingers 46 or up to the stops 3 carrying-tapes 1 50 are stretched from pulleys 16 near the cylinder to pulleys 17, mounted on the shaft 45, which tapes are driven at an appropriate speed by means of a pinion 12 on the shaft of tape-pulleys 16 and an intermediate 11, geared 55 with a toothed wheel 10 on the cylinder-shaft. Each printed sheet as it leaves the impression-cylinder C is guided by the conductors 7 onto the tapes 1, and by the latter is moved outward in a slightly-inclined plane over the 60 fingers 46 until it reaches the stops 3, which are then in their depressed position, as seen in Figs. 1 and 5. The leading ends of the sheets thus arrive directly beneath the margin-rollers 90, which are then raised so as to 65 be non-operative and so held by the levers 82. As soon as the sheet has reached this position the delivery-carriage begins its outward

stroke, during which, although the rack 64 rotates the ratchet-wheel 63, the pawl 9 drags inactively over the same. During the initial 70 movement of the outward stroke of the carriage the arms 80, which support the margin-rollers 90, are held in their upper position by reason of the rock-arm 81 being locked in its forward position by the detent or locking lever 82. When, however, this outward movement has proceeded for a short distance or before the outward stroke of the delivery-carriage is completed, the lever 82 is raised by contact with the tappet 6, thus tripping the 80 lever and causing it to release the rock-arm 81, which then being free to rock permits the margin-rolls 90 to drop upon the delivery-roller 50, upon which they nip the sheet, so that it will partake of the movement of the 85 said delivery-roller when the same takes place. The shaft 41 rocks downward simultaneously with the descent of the rolls 90, thus causing the rock-arm 8, by reason of its confinement in the detent-arm 2, to move the 90 shaft 42 slightly upward, thus raising the stop 3 out of the pathway of the sheet, which is then free to move beyond them.

When the outward stroke of the delivery-carriage has been completed, the sheet will 95 be in a position overlying the piling-table, as in Fig. 3. A reverse movement of the carriage then being made, the delivery-roller 50 will be rotated by means of the wheel 63, then driving the same by engagement of its 100 ratchet-wheel 62 by the pawl 9, carried by the intermediate 61, which latter drives the pinion 60 on the shaft of the delivery-roller, the result of which is, as seen in Fig. 4, that the sheet theretofore transported by the fingers 46 is carried off from the fingers by being rolled out between the margin-rolls 90 and the delivery-roller 50, being thus laid upon the piling-table 99 or the previously-printed sheets accumulated thereon. As the delivery-carriage again approaches the impression-cylinder to receive another sheet the rock-arm 81 will contact with the stop 19, thus raising the margin-rolls 90 and dropping the stops 3, while the lever 82, passing beyond the tappet 6, gravitates to lock the arm 81 and hold 115 said rolls in their raised position. Thus each succeeding sheet delivered by the impression-cylinder C is guided therefrom by the conductors 7 and is propelled over or onto the 120 fingers 46 by the tapes 1, which movement is suspended by contact with the stops 3, when the sheet, which is thus laid upon the fingers 46 printed side up, is nipped by the margin-rolls 90, carried outward over the piling-table 125 by the moving carriage, and there deposited by the rolling action of the delivery-roller 50, no mechanism or device having contacted with its freshly-printed surface, which is up- 130 permost.

In order to attain the highest speed, it is desirable that the tripping action whereby the margin-rolls are brought into active relation to the delivery-roller shall take place at

some time during the outward stroke of the carriage, but the mechanisms will be effective if the margin-rolls are suspended by contact of the arm 81 with the stop 19, as in Fig. 5, while the sheet is running, said margin-rolls descending at once to nip the sheet as the carriage takes up its outward stroke and the rock-arm 81 leaves the stop 19. This would dispense with the lever 82 and its operative devices.

What is claimed is—

1. The combination with a sliding sheet-delivery carriage, and means for reciprocating the same between its sheet-receiving position and over the piling-table, of a rotating delivery-roller 50 and margin-rolls 90 supported by the carriage and operating first to nip the sheet during the outward movement of the carriage, and then to positively roll the sheet therefrom during the return stroke of the carriage, onto the piling-table, substantially as described.

2. The combination with a sliding sheet-delivery carriage, carrying tapes propelling the sheet onto the carriage, and means for reciprocating the carriage from its sheet-receiving position to one over the piling-table, of means on the carriage operating by nipping contact to hold the front edge of the sheet during the outward movement of the carriage and to positively roll the sheet from said carriage, during its return stroke, onto the piling-table, substantially as described.

3. The combination with a sliding sheet-delivery carriage, and means for reciprocating the same between its sheet-receiving position and over the piling-table, of a rotating delivery-roller 50 and margin-rolls 90 moving with the carriage and operating first to nip the sheet during the outward movement of the carriage and then to positively roll the sheet from said carriage during its return stroke onto the piling-table, and a fixed rack 64 and intermediate mechanism driven thereby to revolve the roller 50, substantially as described.

4. The combination with a sliding sheet-delivery carriage, means for reciprocating the same between its sheet-receiving position and over the piling-table, a rotating delivery-roller 50, and margin-rolls 90 moving with the carriage and operating first to nip the sheet during the outward movement of the carriage, and to positively roll the sheet from said carriage during its return stroke onto the piling-table, of a fixed rack 64, pinion 60 revolved thereby, and a clutch mechanism intermediate of the rack 64 and pinion 60, whereby the latter is rotated in one direction only, substantially as described.

5. The combination with a sliding sheet-delivery carriage, means for reciprocating the same between its sheet-receiving position and over the piling-table, and rotating devices supported by the carriage and operating by nipping contact therewith to nip and hold the sheet during the outward movement of the

carriage, and to positively roll the sheet from the carriage onto the piling-table, of means for bringing the same into coactive relation to nip the sheet, substantially as described.

6. The combination with a sliding sheet-delivery carriage, means for reciprocating the same between its sheet-receiving position and over the piling-table, rotating devices for 75 rolling the sheet from the carriage onto the piling-table, and means for bringing the same into coactive relation to nip the sheet, of sheet-stops and means for vibrating them, substantially as described.

7. The combination with a sliding sheet-delivery carriage, means for reciprocating the same between its sheet-receiving position and over the piling-table, a delivery-roller and margin-rolls for rolling the sheet from the 85 carriage onto the piling-table, of a rock-arm 81, and stop 19 whereby the margin-rolls are controlled in relation to the delivery-roller, substantially as described.

8. The combination with a sliding sheet-delivery carriage, means for reciprocating the same between its sheet-receiving position and over the piling-table, a delivery-roller and margin-rolls for rolling the sheet from the carriage onto the piling-table, of a rock-arm 95 81, locking-lever 82 and tripping device, whereby the margin-rolls are brought into coactive relation with the delivery-roller, substantially as described.

9. The combination with a sliding sheet-delivery carriage, means for reciprocating the same between its sheet-receiving point and over the piling-table, a delivery-roller and margin-rolls for rolling the sheet from the carriage onto the piling-table, a rock-arm 105 81 and locking-lever 82, and a tripping device whereby the margin-rolls are brought into coactive relation to the delivery-roller, of a stop, as 19, for raising the margin-rolls, substantially as described.

10. The combination with an impression-cylinder and sheet-propelling tapes leading outward therefrom, of a reciprocating sheet-delivery carriage consisting essentially of fingers 46 for receiving and transporting the 115 sheets, a delivery-roller, as 50, propelled in one direction only, and margin-rollers, as 90, substantially as described.

11. The combination with an impression-cylinder and sheet-propelling tapes leading 120 outward therefrom, of a reciprocating sheet-delivery carriage consisting essentially of fingers 46 for receiving and transporting the sheets, vibrating sheet-stops, a delivery-roller, as 50, propelled in one direction only, and 125 margin-rollers, as 90, substantially as described.

In testimony whereof I have hereunto set my hand in the presence of two subscribing witnesses.

THOMAS M. NORTH.
